INVENTOR:

Louis J. Gerson,
By his attorney,
Franklin C. Gerson

UNITED STATES PATENT OFFICE.

LOUIS JAY GERSON, OF PHILADELPHIA, PENNSYLVANIA, ASSIGNOR OF ONE-HALF TO CHARLES HERITAGE, OF SAME PLACE.

TELEPHONIC ATTACHMENT.

SPECIFICATION forming part of Letters Patent No. 546,972, dated September 24, 1895.

Application filed January 14, 1895. Serial No. 534,740. (No model.)

To all whom it may concern:

Be it known that I, LOUIS JAY GERSON, of the city and county of Philadelphia, State of Pennsylvania, have invented an Improvement 5 in Telephonic Attachments, of which the following is a specification.

My invention relates to attachments for telephones; and it consists of certain improvements which are fully set forth in the following 10 specification, and are shown in the accompanying drawings.

More particularly my invention is a speaking attachment to be applied to the transmitters of telephone instruments, and is designed 15 to enable the person using the instrument to move the speaking-tube into any position desired to suit his height or the position in which he may be standing.

It is also an object of my invention to accomplish 20 this result while preserving a straight open passage for the voice through the tube upon the vibrating plate of the transmitter, so that the transmission of the vibrations is in no way obstructed by the adjustment of 25 the tube.

In carrying out my invention I employ a suitable frame adapted to be attached to the box of the transmitter, with a speaking-tube connected therewith by a universal joint.

Referring to the accompanying drawings, Figure 1 is a perspective view of a telephone having my improved attachment applied. Fig. 2 is an enlarged longitudinal sectional view of my improved attachment. Fig. 3 is 35 a perspective view of the same; and Fig. 4 is a perspective view of the detached tube, illustrating a modification.

The attachment consists of a frame A, adapted to be clamped or otherwise attached 40 to the transmitter, and a tube B connected with the frame A by a universal joint, whereby the tube may be turned in any desired direction to suit the elevation or position of the mouth of the person using the instrument.

45 My preferred construction of the universal joint consists of a ball and socket C, as shown in the drawings.

The frame A is constructed with an aperture D, adapted to occupy a position over the

mouthpiece of the transmitter, adjacent to 50 which is a ball-shaped socket adapted to receive the ball-shaped end of the tube A.

The ball-shaped socket is preferably constructed of flanges E F, extending from the inner and outer faces, respectively, and properly 55 curved to form the ball-socket, open at its inner side, to the mouthpiece of the transmitter, and at its outer side to receive the tube and permit the desired movements.

The tube B is shown provided with an enlarged ball-shaped end G, adapted to fit within the socket formed by the flanges E F, and to turn freely therein. The inner end of the tube is open to the mouthpiece of the transmitter. The outer end of the tube B is shown provided with a suitable flaring mouthpiece H. With the tube B connected with the frame A in this manner it is possible, while permitting the tube to be turned in any desired direction, to preserve a straight open line from 70 the mouthpiece H directly upon the vibratory plate of the transmitter. The tube may be easily turned in any direction, either up or down, to suit the height of the person speaking, or to the right or left to suit convenience 75 or position of the instrument. In whatever position the tube may be turned the voice will be thrown directly upon the transmitter. The tube B may be made in telescoping or sliding sections, as shown in Fig. 4, so that it may be 80 lengthened or shortened when desired. The frame A may be secured to the transmitter-box in any desired manner. I have shown it provided with flanged clamping-edges I, adapted to engage the rim of the box. 85

These and other details of construction may be varied without departing from the invention.

What I claim as new, and desire to secure by Letters Patent, is—

1. A speaking attachment for telephones, consisting of an attaching frame, and a speaking tube connected therewith by a ball and socket joint, whereby the tube may be turned in any direction.

2. A speaking attachment for telephones, consisting of an attaching frame A having an aperture D, and a ball shaped socket about

the aperture, and a tube B having an open ballshaped end G adapted to fit the ball shaped socket of the frame A.

3. A speaking attachment for telephones, 5 consisting of an attaching frame A having an aperture D and flanges E, F, in the inner and outer faces respectively forming a ball shaped socket, and the tube B having the ball end G

adapted to fit the ball shaped socket composed of the flanges E, F.

In testimony of which invention I have hereunto set my hand.

LOUIS JAY GERSON.
